UNITED STATES PATENT OFFICE.

LOUIS SCHUTTE, OF PHILADELPHIA, PENNSYLVANIA.

VALVE CONSTRUCTION.

SPECIFICATION forming part of Letters Patent No. 740,186, dated September 29, 1903.

Application filed October 28, 1901. Serial No. 80,260. (No model.)

To all whom it may concern:

Be it known that I, LOUIS SCHUTTE, a citizen of the United States of America, residing in the city and county of Philadelphia, in the State of Pennsylvania, have invented a certain new and useful Improvement in Valve Construction, of which the following is a true and exact description, reference being had to the accompanying drawings, which form a part thereof.

My invention relates to the construction of valves used in connection with steam-conduits, and has for its object to provide for the renewal and adjustment of the stuffing-box packing surrounding the valve-spindle without subjecting the operative to injury from leaking steam. With this object in view I form the perforation through which the valve-spindle extends with a valve-seat around its inner end, and I connect with the valve or a part moving with the valve a supplemental valve adapted to seat itself upon this seat and close the perforation when the main steam-valve is raised. The stuffing-box is of course situated at some point in the perforation above the valve-seat, and I form in the perforation between the valve-seat and the stuffing-box a chamber adapted to receive any steam which leaks beyond the valve, said chamber having an escape-orifice through which the steam can pass without endangering the operative who is repairing the stuffing-box. Of course this escape-orifice must be provided with some means for closing it under normal conditions.

Reference being now had to the drawings in which my invention is illustrated, Figure 1 is a sectional elevation of a portion of a valve-casing and valve with actuating mechanism, said drawings showing one modification of my invention. Figs. 2, 3, and 4 are similar sectional elevations showing other modifications of my invention.

A in all the drawings indicates the portion of the valve-casing to which my invention is directly applied, as shown the removable cap of the casing.

A' indicates the perforation through which the valve-spindle passes; A², the stuffing-box; A³ in Figs. 3 and 4, a threaded portion of the perforation into which a threaded portion of the valve-spindle screws. a³, Fig. 1, indi-

cates a similar thread, in this case, however, formed in a thimble B, inserted at the top of the perforation and held in place by an annular nut B' and a spline B².

A⁴, Figs. 3 and 4, indicates a valve-seat formed at the inner end of the perforation, and a⁴, Figs. 1 and 2, a similar valve-seat formed in a plate C, which plate is inserted at the base of the perforation A'.

D indicates a plate set in the perforation at the bottom of the stuffing-box D', indicating the stuffing-box gland between which and the plate D the packing is inserted, the gland being held down on the packing by any convenient means—such, for instance, as are indicated in Fig. 4, where it is gripped by a threaded annulus D².

E is the valve-spindle, shown as having a projecting annular flange E' at its inner end and provided with a threaded portion E², which engages the threads A³ or a³ of the perforation. In Figs. 1 and 4 I have shown a hand-wheel E³, secured to the top of the spindle.

K indicates a chamber formed above the valve-seat at the bottom of the perforation and below the stuffing-box. This chamber is provided with an outlet-passage—as, for instance, a channel F, as shown in Figs. 2 and 3—having its end normally closed by a plug F', or the outlet-passage instead of passing through the valve-casing may be formed in the valve-spindle, as shown at f in Figs. 1 and 4, the outer end of the passage being closed normally by a plug f'.

G indicates the steam-valve, which may be of any convenient construction and which is shown as secured to the flanged end E' of the spindle by a clamping-piece of any convenient construction, as is indicated at G' in the different figures.

H, Fig. 1, indicates a valve formed in this modification by a shoulder of the valve-spindle E and fitting when the valve-spindle is raised against the valve-seat a⁴. In Fig. 2 a similar valve H' is formed on the upper end of the clamping-piece G', and this is also the case in Fig. 3, while in Fig. 4 the valve indicated at H² is formed on an upwardly-extending portion of the valve G itself. All that is necessary is that the valve fitting on the seat at the base of the perforation should

be of such a character that it will move up and down with the valve.

In the modification illustrated in Fig. 1 the valve G is provided with a piston extension 5 I, which moves in an open-ended cylinder, (indicated by J,) this being the usual construction and in no wise connected with my present invention.

In operation when it is desired to renew or 10 adjust the packing in the stuffing-box the operator turns the valve-spindle, so as to retract the valve and bring the supplemental valve into tight contact with the valve-seat at the base of the perforation, and where the 15 closure is approximately perfect the operator can then remove the stuffing-box gland and renew or adjust the packing without danger of injury through live steam. As, however, the supplemental valve is only infrequently 20 used, it is quite probable it will not make an entirely-tight closure, and for this reason I provide the intermediate chamber K and outlet-passage F or f, closed by the plug F' or f', and when the supplemental valve is moved 25 up to its seat I remove the plug F' or f', so that any steam passing the supplemental

valve will be intercepted in the chamber K and pass out through the outlet-passage F or f instead of forcing its way through the stuffing-box.

Having now described my invention, what I claim as new, and desire to secure by Letters Patent, is—

In combination with a valve, a perforated portion of the valve-casing and a valve-spindle passing through such perforation, a valve-seat extending around the lower part of the perforation in the casing, a supplemental valve moving with the main valve and acting to contact with said valve-seat and close the 40 perforation in the casing when the main valve is retracted by the spindle, a stuffing-box situated in the spindle-perforation, a chamber between the stuffing-box and the valve-seat and an outlet-passage extending from said 45 chamber for the escape of fluid and a closure for said outlet-passage situated at the outer end thereof.

LOUIS SCHUTTE.
